(57) **CLAIM**

The ornamental design for a reptile cabinet, as shown and described.

DESCRIPTION

FIG. 1 is a front and top perspective view of a reptile cabinet, showing my new design;

FIG. 2 is a front view thereof;

FIG. 3 is a rear view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged view of portion 8 shown in FIG. 2.

The dash-dash broken lines in the drawings represent portions of the reptile cabinet that form no part of the claimed design. The dot-dash broken lines in the drawings denote the boundaries of the enlarged detail view and form no part of the claimed design.
